HEATING MEANS

Robert A. Wittmann, Chicago, Ill., assignor to
Thermek Corporation, Chicago, Ill., a corpora-
tion of Delaware

Application March 23, 1939, Serial No. 263,706

2 Claims. (Cl. 122—333)

The invention relates to liquid heaters.

In many water-heaters the water is circulated through one or more tubes and heated by the hot flue gases from a gaseous fuel burner such as blue water gas, producer gas, carbureted water gas, natural gas, and various mixtures thereof. These gases have a high hydrogen content so that the flue gases from the combustion thereof have considerable moisture or vapor content.

10 The combustion of ethane C_2H_6 may be taken as an example. On complete combustion, such flue gas sometimes contains approximately 30% water vapor content by weight. The temperature of the flue gases produced by the combustion of these gaseous fuels is usually over 2000° F. The dew points of gases having a high hydrogen content range upwardly from 100° F.

The heating tubes in these heaters through which the liquid flows are usually at a considerably lower temperature than the dew point of the hot flue gases. For example, when water at 70° F. is flowing through a heating tube, the temperature of the outside of the tube may be approximately 80° F. The temperature of the surfaces extending from the heating tube and adjacent thereto will be 80° F. or somewhat higher. When heat transfer elements, such as fins, are used on the heating tube and a temperature of approximately 80° exists on the outer surface of the tube and the surfaces of the fins, there will be a zone between the wall of the tube and the flue gases passing around the tube at a temperature below the dew point while the heat transfer surfaces farther away from the tube wall will be at a higher temperature, such as 600° F. or more and this condition resulted in condensate where the flue gases contacted with the portions of the surfaces of the tubes and said elements having temperatures below the dew point.

40 In constructions heretofore used, the condensate from the flue gases on the heating tubes and transfer elements in the zone at a lower temperature than the dew point of the flue gases, caused small percentages of SO_2 and other acidic constituents to be entrained in the condensed water vapor, which bring about corrosion of the cold surfaces and thereby reduce the efficiency of the transfer elements and shorten their life. In some instances the water vapor condenses in sufficient quantity to drip down on the gas-burner and close the gas-ports thereof, which produces conditions which are undesirable both from structural and functional viewpoints.

55 One object of the invention is to provide a heater of this type in which condensation from

the hydrogen content of the hot fuel gases will not be produced and deposited on the heating tubes or the heat transfer elements on the tube.

Another object of the invention is to provide a water or liquid heater in which the flue gases are prevented from coming into contact with those portions of the heater-tube and its heat transfer elements in the zone around the tube where temperatures below the dew point are maintained.

10 Another object of the invention is to provide a method of preventing moisture condensation from hot flue gases on the heating surfaces by shielding the latter where the temperatures below the dew point of the hot flue gases exist or 15 are maintained.

The invention consists in the several novel features which are hereinafter set forth and are more particularly defined by claims at the conclusion hereof.

20 In the drawings: Fig. 1 is a vertical section of a heater embodying the preferred form of the invention, the tubular structure through which the water to be heated circulates being shown in elevation. Fig. 2 is a section taken on line 2—2 of 25 Fig. 1. Fig. 3 is a side elevation of a portion of one of the heater tubes with the heat spines thereon. Fig. 4 is a section on line 4—4 of Fig. 3. Fig. 5 is a section on line 5—5 of Fig. 3. Fig. 6 is a section of a heater embodying a modified 30 form of the invention. Fig. 7 is a section on an enlarged scale of a section of the heater tube of the form of the invention shown in Fig. 6. Fig. 8 is a section on line 8—8 of Fig. 7. Fig. 9 is a section of another modification.

35 In Figs. 1 to 5 the invention is exemplified in a heater comprising a jacket or body *a* and a series of heater-tubes with the hot flue gases blowing substantially parallel to the tubes, a gas burner *b* in the lower portion of the body and an outlet *a*¹ for the products of combustion. The structure through which the water or liquid to be heated is circulated comprises an inlet-header *15* into which water is delivered through a supply-pipe *16*; a series of vertical tubes *17*, the lower ends of which are secured in branches of header *15* so that water will flow from the header upwardly from said tubes; an outlet-header *18* in which the upper ends of the tubes *17* are secured; and an outlet pipe *19* for the heated 50 water or liquid leading from header *18*. Each tube *17* is provided with helical series of spines 55 gouged from the stock in and bent to extend outwardly from its wall so that the spines will be integral with the tube. Adjacent the tube-wall

the spines are close together and overlap vertically approximately to the point 21 some distance away from the wall of the tube. The spines extend outwardly from the point 21 and are tapered to pointed ends 22 and diverge from one another outwardly from point 21 sufficiently to form V-shaped spaces 23 between them through which the flue gases can pass. Horizontal baffles 24 and 25 are secured in the body and are provided with openings 26 which conform substantially to the outer ends of the spines to confine the hot flue gases in their upward passage to the spaces 23 between the spines. The close and overlapping formation of the spines 20 to the point 21 results in baffling the hot flue gases to substantially exclude them from the zone between the points 21 and the peripheries of the tubes. The spaces 23 between the spines permit the hot flue gases to pass upwardly through the body and to contact with the spines for efficient heat transfer to the heating-tubes 17.

In the operation of this form of the invention the temperature of the hot flue gases rising from the burner b^1 is usually, and may be assumed to be, 2000° F. The dew point of the hydrogen content in certain gaseous fuels will not exceed 138° F. In transit through the heater body a the flue gases will be cooled by contact with spines 20 and leave the outlet a^1 at approximately 350°. The temperature at the outer ends of the spines will be approximately 600° F. and, by reason of their high ratio of exposed area to their mass, serve as efficient heat transfer elements or conductors to the tubes 17. The temperature at the points 21 of the spines will be somewhat more than 138° F. The temperature of the water as it passes through the tubes 17 increases from an approximate temperature of 70° at mid-height of the tubes while the temperature of the tube-wall may be approximately 80° F.

The flue gases will pass upwardly through spaces 23 between the spines and the closely arranged and overlapping root-portions of the spines will form a baffle for the hot flue gases which will exclude them from the zone between points 21 and the wall of the tube. As a result, the flue gases will be substantially excluded from the zone around the heating tube at which temperatures below the dew point exist. As a result, no condensate will be deposited on the spines or tubing, there will be no corrosion of the tubing and spines, and the other objections from the production of condensate will be overcome.

This form of the invention exemplifies a heater in which the hot flue gases travel substantially parallel with the tubing and the latter is provided with spines, the outer portions of which are contacted by said gases for heat transfer to the tube and the root portions of the spines serve as a baffle for excluding the hot gases from a zone around the tubing where the temperature is so low that the hydrogen or water vapor would be condensed if it were not excluded therefrom. The supply pipe 16 is provided with a cylindrical sleeve 16^a between the wall of body a and heater 15 to prevent condensate forming on the portion of the supply pipe within the body.

In Figs. 6, 7 and 8, the invention is exemplified in a hot water heater in which the fuel gases flow transversely to the tubing. The heater comprises a body a^2 , a gas burner b^1 , and an outlet a^3 for the products of combustion at the top of the body. A water supply pipe 16^a is connected to a tube 30 which is looped back and forth across the heating chamber in the body and is connected

to a hot water outlet 31. Fins 32 are spaced apart lengthwise of, and secured on, each of the horizontal portions of the tube 30 for heat transference to the tube. Each fin has a central portion 33 which fits snugly around the outer periphery of the tube 30, a relatively offset outer portion 35 and a cylindrical wall 34 spaced outwardly from the tube and connecting portions 33, 35. The cylindrical portions 34 serve as spacers between the fins and form a continuous cylindrical baffle around the outer periphery of the tube 30.

In this construction the flue gases flow vertically between and contact with the fins for heat transfer to the tube. The cylindrical portions 34 forming the baffle are so spaced from the outer face of tube 30 that the flue gases will not contact with the tube 30 but only with the cylindrical baffle. When the temperature of the water flowing through the tube ranges from 70-80° F. the hot flue gases of approximately 2000° F. will contact with the fins and the outer portions of the baffle and maintain a temperature around the baffle ranging from 600° F. at the outer ends of the fins downwardly to a point which will maintain the temperature around the baffle above 138° F., the dew point of certain hot flue gases. As a result, the hot gases will not contact with any wall, the temperature of which is below the dew point, and no condensation will take place on the fins or on the baffle and slow corrosion of the tube and the fins will be avoided. The dripping of water onto the burner b^1 will also be prevented. This exemplifies a form of the invention in which the hot flue gases flow transversely to the tubing. The tube 30 between the outer fins a and the surrounding wall of the body a^2 is shielded by cylindrical sleeves 36 which are spaced from the tube to prevent condensation on these portions of the tube outside of the fins a . In Fig. 9, the invention is exemplified in a construction embodying fins a^4 in the form of discs the inner edges of which are fitted around the tube 31 and cylindrical sleeves 39 spaced from the tube and extending between the discs.

It will be understood that the temperatures referred to are typical and may be modified according to the particular conditions existing in different heaters so long as the principle of excluding the hot flue gases from the zone around the tubing where temperatures below the dew point exists.

The invention is not to be understood as restricted to the details set forth, since these may be modified within the scope of the appended claims, without departing from the spirit and scope of the invention.

Having thus described the invention, what I claim as new and desire to secure by Letters Patent is:

1. In a liquid heater, the combination of a burner for gaseous fuel having a hydrogen content, a tube through which the liquid flows, extending longitudinally of the flow of the combustion gases from the burner, and heat-exchange spines integral with and extending outwardly from the outer periphery of the tube, said spines having their inner portions formed sufficiently close together to exclude the hot flue gases from the surfaces of the tube and the portions of the spines adjacent the tube in the zone where the temperatures are below the dew point, for preventing condensation of water vapor in the gases and on the tube and spines.

2. In a liquid heater, the combination of a

burner for gaseous fuel having a hydrogen content, a tube through which the liquid flows, extending longitudinally of the flow of the combustion gases from the burner, and heat-exchange spines integral with and extending outwardly from the outer periphery of the tube, said spines having their inner portions formed sufficiently close together to exclude the hot flue gases from the surfaces of the tube and the

portions of the spines adjacent the tube in the zone where the temperatures are below the dew point, for preventing condensation of water vapor in the gases and on the tube and spines, the outer portions of the spines having pointed ends so as to form outwardly divergent V-shaped gaps between them through which the gases flow longitudinally of the tube.

ROBERT A. WITTMANN.
